[57] CLAIM

The ornamental design for an access door with integral latch, as shown and described.

DESCRIPTION

FIG. 1 is a front elevational view of an access door with integral latch showing my new design;

FIG. 2 is left side elevational view thereof, the right side elevational view being substantially a mirror image of the side shown;

FIG. 3 is front perspective view thereof; and,

FIG. 4 is rear perspective view of an access door with integral latch.
